(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view taken along line 8-8 in FIG. 2.

The evenly dashed broken lines in the drawings show portions of the mobile phone that form no part of the claimed design. The dot-dash line is an imaginary line that is included for reference purposes only to identify the cross-sectional view; the dot-dash line forms no part of the claimed design.
